Attorney

UNITED STATES PATENT OFFICE.

FRANK F. FULLER, OF ROCKY FORD, COLORADO.

HARROW.

1,176,047.

Specification of Letters Patent. Patented Mar. 21, 1916.

Application filed August 21, 1915. Serial No. 46,696.

To all whom it may concern:

Be it known that I, FRANK F. FULLER, a citizen of the United States, residing at Rocky Ford, in the county of Otero and State of Colorado, have invented certain new and useful Improvements in Harrows, of which the following is a specification, reference being had to the accompanying drawings.

10 This invention relates to certain improvements in harrows and has relation more particularly to a device of this general character, especially designed and adapted for use as an attachment for a cultivator and it is an object of the invention to provide a harrow of this general character having novel and improved means whereby it may be readily and effectively secured in applied position.

20 It is a further object of the invention to provide a novel and improved harrow of this general character including means whereby it may be adjusted to varying widths in accordance with the requirements 25 of the practice.

The invention consists in the details of construction and in the combination and arrangement of the several parts whereby certain important advantages are attained and 30 the device is rendered simpler, less expensive and otherwise more convenient and advantageous for use, all as will be hereinafter more fully set forth.

The novel features of the invention will 35 be carefully defined in the appended claims.

In order that my invention may be the better understood, I will now proceed to describe the same with reference to the accompanying drawings, wherein—

40 Figure 1 is a perspective view of a harrow constructed in accordance with my invention; Fig. 2 is an enlarged horizontal section taken on the line 2—2 of Fig. 1; and Fig. 3 is a detail elevation of one of the 45 toothed clamping plates.

As herein disclosed, 1—1 denotes the side beams of my improved harrow, having their forward extremities pivotally connected, as at 2, whereby a relative adjustment of said 50 side beams may be had in order to meet the requirements of practice and operatively engaged with each of said side beams are the teeth 3, preferably of the well known diamond type. These teeth are removably 55 and adjustably secured upon the beams of

the harrow by means of clamping plates, indicated at 12. This plate is provided in its inner face with the groove or channel 13 to receive the tooth 3, and in one end of the plate, a series of notches or recesses 14 are 60 formed. Adjacent to the other end of said plate, a transversely disposed opening 15 is provided.

16 designates a U-shaped clamping bolt which is adapted to be engaged through 65 spaced openings in the beam 1, one of said openings coinciding with the opening 15 in the clamping plate. Through these coinciding openings, one of the arms of the U-shaped bolt is engaged, while the other arm 70 is seated in one of the notches 14 in the end of the clamping plate and disposed through the other opening in the beam. Suitable nuts 17 are threaded upon the ends of the bolt arms. It will be readily understood 75 that the clamping plate may be easily and quickly adjusted upon the beam by engaging the arm of the bolt in the desired recess 14 so as to position the harrow tooth at an angle with respect to the cultivator beam. 80

Each of the side beams at a predetermined point intermediate its length, is provided with the inwardly disposed plate or arm 4. The plates or arms 4 are in overlying relation and are provided with the longitudinally spaced openings 5, adapted to register and through which the clamping bolt 6 is directed, in order to maintain the side beams 85 1 in their various relative adjustments.

7 denotes an upstanding member of pre-determined dimensions having its lower extremity provided with the rearwardly disposed extension 8 adapted to be engaged by the clamping bolt 6, while the upper extremity of said member is adapted to be clamped 95 in any desired manner to the frame of a cultivator. As the cultivator may be of any type desired, it is thought that an illustration or description thereof is unnecessary. Intermediate its length the member 7 is provided with the forwardly disposed and downwardly inclined bar 9 having its lower or free extremity provided with a lateral extension 10, through which is disposed the pivoting member 2, whereby it will be perceived that the member 7 is effectively braced in applied position. I also find it of advantage to suitably secure to the extension 10, a chain 11 or other flexible member which is adapted to be suitably secured to 110

the cultivator, whereby the member 7 is relieved of a certain extent of the operating strain.

From the foregoing description, it is thought to be obvious that a harrow for attachment to a cultivator constructed in accordance with my invention, is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice.

Having thus described this invention, what I claim is:

1. A harrow of the character described comprising two side beams, having adjacent extremities pivotally connected, inwardly disposed arms carried by the side beams and arranged in overlying relation, said arms being provided with longitudinally spaced openings adapted to register, a clamping bolt disposed through said open-

ings, an upstanding member having its lower extremity operatively engaged with the clamping bolt, and a brace bar projecting forwardly from the upstanding member and operatively engaged with the pivotal connection between the side beams.

2. A harrow of the character described comprising two side beams, having adjacent extremities pivotally connected, inwardly disposed arms carried by the side beams and arranged in overlying relation, said arms being provided with longitudinally spaced openings adapted to register, a clamping bolt disposed through said openings, an upstanding member having its lower extremity operatively engaged with the clamping bolt, a brace bar projecting forwardly from the upstanding member and operatively engaged with the pivotal connection between the side beams, and a flexible member operatively engaged with the brace bar.

In testimony whereof I hereunto affix my signature in the presence of two witnesses.

FRANK F. FULLER.
